ADJUSTABLE REAMER.

Application filed December 18, 1924. Serial No. 756,744.

This invention relates to tools and machines for cutting and polishing circular bearings and is directed particularly to an improved tool for treating connecting rod bearings.

One feature of the invention includes the combination of a reamer and burnisher in which the parts are adjustable. This is particularly useful as a fixed bench tool.

10 Another feature includes the arrangement in a device of the type described of adjustable and expansible arms extending from a fixed mounting which mounting also carries the adjusting mechanism.

15 Another feature relates to the adjustment of the arms equally from a common center, the arms having cutting and polishing surfaces on the outer portions and lengthwise of the arms.

20 The above features and additional advantages of the invention are described and claimed in the following specification and claims, and illustrated in the accompanying drawing, in which:

25 Figure 1 represents a side elevation of the tool mounted on a bench, illustrating the fixed head in the central portion, the combined reamer and broacher surfaces at the right, and the adjusting mechanism at the left;

Figure 2 is a front view in elevation looking directly at the center of the tool;

Figure 3 is a longitudinal sectional view of the tool taken on the line 3—3 of Figure 2;

Figure 3^a is a modified view of the parts shown in Figure 3 illustrating the parts in the loosened position with the arms ready for adjustment;

40 Figure 4 is a sectional view taken on the line 4—4 of Figure 3;

Figure 5 is a sectional view of the adjustable arms taken on the line 5—5 of Figure 1;

45 Figure 6 is a side view of the head portion with the retaining plate removed, looking in the direction of the arrow in Figure 4; and

Figure 7 is an enlarged fragmentary, cross sectional view of one of the cutter arms shown in section in Figure 5 and illustrating the respective position of the cutting edge and the burnishing surface.

Like reference numerals refer to like parts in the various figures.

50 Referring in detail to the drawings, I in-

dicates the fixed head portion having a front face 1^a, and a rearwardly extending boss 1^b projecting as a cylindrical portion. Supporting means for rigidly securing the head 1 to a work bench is indicated at 2 by 60 legs or braces fastened to the under side of the head 1 by fastening screws 2^a and secured by suitable bolts 2^b to a horizontal support 2^c. Adjustable cutter arms 3, 4 and 5 are mounted in the head 1 and project from the face 1^a in a parallel arrangement. These arms, as shown in Figure 5, are formed as sectors positioned about a central member which will be further described, and they are capable of adjustment radially and equally from this central member. The head 1 is provided with a series of radially extending slots, corresponding in number to the number of the arms, and in this case identified by the 70 numerals 6, 7 and 8, in which are mounted the respective cutter arms 3, 4 and 5. The side walls of each slot in the figures are indicated by the numerals 6, 7 and 8, and the back wall is indicated by the numeral 6^a, 80 7^a and 8^a. These slots are shown as having square corners, and the corresponding portion of the cutter arms is preferably formed to have a fairly close sliding fit with the walls of the slot. The arms are thus firmly 85 and rigidly mounted in the head and project from one face thereof, and in other words, from one extreme side wall thereof, and the arms are thus supported at one end only by and project from the walls of the 90 slots in the face. This is in contrast to known types of radial movable cutters, such as pipe cutters or expanders, wherein the movable parts are slidable in a slot, the walls of which embrace both ends and possibly also the side portions of the movable parts. Obviously the walls of the slot might have some other shape and this is immaterial so long as the cutter arms are firmly 95 mounted therein for radial adjustment. The 100 parallel arms must remain parallel in all adjustments for the reason that they are thus firmly held for radial movement only. The device includes particular means for providing for ease in adjustment of the 105 arms and also for renewing the parts which may become worn by frequent adjustment of the arms in the slots. This means includes the use of a series of keyway members 9 which are substantially circular in 110

cross section and which are positioned one on either side of the cutter arms within the slots. These members 9 are inserted in substantially the following manner. A half round groove is formed in the side wall of the slot and within the head portion, as indicated at 10, and a corresponding half round groove is formed in the arm portion, as indicated at 11. Together these grooves 10 form a keyway which is round and which is capable of receiving the cylindrical pin 9. The half round keyways may be formed by drilling a hole when the cutter arm is in position in its slot. Each member 9 has a laterally extending lug 9^a engaging a corresponding depression in the member 1 to prevent the key members from turning. Whenever wear of the parts tends to loosen the connection between the cutter arms and the key members, the key members may be renewed and lost motion eliminated. A retaining plate 12 is provided to bridge each of the slots and to prevent the removal of the pins 9, and to limit the extreme radial movement of the cutter arms. These retaining plates 12 have depressions on their inner faces indicated at 12^a which are substantially between the respective pairs of key members 9. A corresponding depression is formed in each of the cutter arms between the respective pairs of key members as indicated at 3^a, 4^a and 5^a. In each pair of depressions is mounted a spring 13 which thus extends in a position substantially parallel to the key member in each slot. This spring 13 normally exerts a pressure on the cutter arm and tends to keep it in its central position and against the central actuating shaft, as will be described. Suitable fastening screws 12^b are provided for securing the plates on the head 1, and the head 1 may be provided with a flattened portion 1^c adjacent each slot if the under face of the plate member 12 is provided with a corresponding plane surface, as illustrated in the drawings. The head 1 has screw threaded openings 12^c for the reception of the fastening screws 12^b, and it also has a pin 12^d which is adapted to fit into a corresponding hole in the plate to assist in the proper and ready positioning of the plate over the slot opening.

The peculiar shape of the cutter arms will be understood by referring to the sectional views 3 and 5. The cutter arms 3 and 4 are substantially identical in shape, and each has on it two relatively flat faces 14 which are not cutting faces and are not intended to come into contact with any surface treated. Cutting edges are indicated at 15, and these are similar to known forms of reamer cutting edges in that they extend lengthwise. Work is reamed when it is moved counter clockwise, looking at Figure 2. The cutting edges 15 lie in the arc of a circle passing through them and the center of

which is in the axial work center of each of the arms which happens to be the center of the shaft 19, to be described. The present arrangement has radially adjustable arms, each provided with a cutting edge. Each 70 arm has a burnishing surface 16 which serves to smooth and polish the metal treated whenever the work is moved clockwise, which is in a reverse direction from the usual reaming movement and which is 75 counter-clockwise looking at Figure 2. This burnishing surface 16 extends from the cutting edge to the left end with a gradually decreasing curved surface which is less than that of the curve of the path of travel of the cutting edge. The curvature of this surface is thus not the same as the arc of a circle which would pass through the cutting edge 15 and have its center on the central work axis of the arm. The cutter arm 5 has no cutting edge 15, but has its entire outer surface curved and smooth, as indicated at 17. This surface 17, mentioned in the claims as a work-engaging 80 surface, extends lengthwise of the arm 5 and substantially the full length thereof. It will be noted that burnishing surfaces 16 lie alongside of the cutting edges terminating at one side in the cutting edge, and are substantially co-extensive with the length of the cutting edges. Each of the arms 3, 4 and 5 has cutting portions 18 formed on the curve next adjacent the head end of the arms, which cutting portion is a radial reamer for treating the curved edges of bearings. Each of the cutter arms has a shoulder in engagement with the face 1^a of the head portion, which shoulder is merely a continuation of the arm on either side of the slot opening.

Actuating means for adjusting the position of the arms 3, 4 and 5 is provided by a central shaft 19 which has a tapered portion extending from the head 1 in engagement with a corresponding tapered surface on the central side of each of the cutter arms. The opposite end of the shaft 19 is provided with screw threads 20 in engagement with corresponding threads in the head, and movement of the threaded portion serves to advance or retract the conical portion 19. Between the portions 19 and 20 is an intermediate cylindrical portion 21 which is fitted into a corresponding circular bearing portion in the head, and which serves to maintain the alignment of the actuating shaft with respect to the head and arms. The extreme end portion of the shaft 19 is provided with screw threads 22, on which are mounted the fastening means for securing the free ends of the cutter arms, as will be described. The rear end or threaded end of the shaft is provided with a grip or handle portion 23 which is keyed at 23^a to the shaft 19, and which is provided with a

fastening screw 23^b, thus effectively preventing relative rotation or endwise movement of the part 23 with respect to the shaft. The grip portion 23 has a forward portion 23^c formed as an annular shell adapted to encircle the cylindrical surface of the part 1^b, and also adapted to receive thereon calibrations to assist in the accurate adjustment of the parts. On the cylindrical outer surface of the portion 1^b is provided a lengthwise extending line 1^d, which serves as an index for use with the calibrations on the part 23^c. Extension gripping means is provided by the screws 23^d fitted into the grip portion 23 and thus constituting a star wheel. In order that wear may be eliminated and lost motion prevented, the shaft 19 is provided with a removable sleeve 1^e, which is fitted into the head portion 1 from the rear end thereof. This portion 1^e contains the threads for engagement with the thread 20 and the cylindrical bearing surface in which the portion 21 slides.

The parallel cutter arms extend from the head and terminate with substantially free ends. Fastening means for securing the free ends in any predetermined position is provided by the following combination of parts. The ends of the cutter arms 3, 4 and 5 are tapered down sharply providing the inclined surface 24 on each arm. The inside of each arm is likewise tapered down from the outer end inwardly providing corresponding inner inclined surfaces 25 on each arm. On the threaded portion of the shaft is a cone shaped nut 26 having the small end thereof adapted to fit into the inner inclined faces of the cutter arms. This nut 26 has a rear portion 26^a which is screw threaded to the threaded portion of the shaft, and a forward portion 26^b which is not screw threaded, but is provided with a cut away portion next to the shaft so as to enable it to move along the shaft and to project part way over the tapered portion of the member 19. This nut 26 is thus adapted to support the free ends of the cutter arms against movement centrally. Locking means for holding the free ends of the cutter arms firmly against the conical nut 26 is provided by an annular cup shaped member 27, which is loosely fitted over the threads 22 of the shaft 19 and has a central opening 27^a. It also has an inclined face 27^b on the inner surface thereof which slopes outwardly and which is adapted to rest on the inclined faces 24 of the cutter arms. A locking nut 28 is screw threaded to the portion 22 of the shaft and is adapted to hold the annular member 27 firmly against the outer ends of the cutter arms and to press them against the conical nut 26. Adjustment outwardly of the parallel arms is effected solely by means of the manipulation of the grip mem-

ber 23 operating through the cam of the shaft 19. The springs 13 tend to return the arms centrally and hold them against the shaft 19. The arms cannot move from the parallel position because they are securely held in the radial slots 6, 7 and 8. To adjust the arms outwardly, it is necessary that the cup shaped member 27 and its locking nut 28 be loose and free from the ends of the arms. To adjust the arms centrally, it is equally necessary that the cone shaped nut 26 be withdrawn so that the arms may close freely to the desired position, after which the nut 26 may be returned to snugly support the ends of the arms, and then the member 27 and the nut 28 may clamp the ends of the arms against the nut 26. The nut 26 and the parts 27 and 28 should not be used to distort the arms from their parallel positions.

Claims to the locking feature are presented in the copending application Serial No. 550,082 to Ewell, Shuey and Vandergrift.

The manner of using the tool will now be explained. A circular bearing, such as a connecting rod bearing mounted in a connecting rod, is moved endwise over the outer end of the cutter arms and the arms are then expanded to the proper operating position by manipulation of the grip member 23. The purpose of this tool is to reduce the metal in any Babbitt or other bearing when the latter is moved in a counter clockwise direction about the cutter arms, presuming that the operator stands facing the side 1^a of the head member 1. The cutting effect is obtained by means of the knife edges 15 on the cutter arms 3 and 4, sufficient clearance being allowed so that the bearing metal will not be cut, torn or pulled, but will be formed into a hardened, smooth, cylindrical surface. This is due not only to the angle in which the edge 15 is cut into the arm but also to the fact that the portion 16 of the arm, directly behind the edge or the heel of the cutting edge, is in contact with the Babbitt metal holding it down and cutting it without tearing or pulling and also compressing it to some extent. In other words, the effect is the same as if a broach had been used. Then, after the arms have been expanded a few thousandths of an inch, the bearing is moved in a clockwise direction, bringing into use the smooth surfaces 16, and there is produced a burnished effect on the bearing metal. No other subsequent treatment is necessary before placing the bearing on its journal. The arms may then be contracted and the bearing slipped off of the end of the arms.

It is important to note the difference between a hand scraped bearing and the effect produced by the tool of this inven-

tion. The use of a hand scraping process leaves a comparatively soft spongy surface which must be hardened and seated by actual contact with the journal while in operation, and subsequently the bearing should be adjusted in order to make it fit properly. With the use of this tool, however, the bearing metal has been seated and the surface glazed to such an extent that the bearing should not require adjustment after operation. The glaze produced on the surface of the bearing by the use of this tool is a live, compressed glaze and not a dry, hard, brittle glaze such as is ordinarily produced when a bearing is burned in with oil.

One of the chief advantages of the use of this tool is the amount of time saved in fitting bearings. In practice it has been found that a set of four connecting rod bearings has been fitted in fifty minutes, as compared to the usual five to ten hours required in fitting hand scraped bearings. The wearing of the bearing produced by the use of this tool is not as rapid as that common to hand scraped bearings.

It is obvious that by means of different sized sets of cutter arms this tool will be capable of use in a wide range of different size bearings.

We claim:

1. In a tool, a cutter arm having thereon a cutting edge, extending lengthwise of said arm, and said arm having an axial work center lengthwise thereof, and a curved and smooth burnishing surface extending lengthwise of said cutting edge immediately adjacent thereto, and the curvature thereof being different than the arc of a circle which passes through the cutting edge and has its center in said axial center.

2. In a tool, a cutter arm having thereon a cutting edge, extending lengthwise of said arm, and said arm having an axial work center lengthwise thereof, and a curved and smooth burnishing surface extending lengthwise of said cutting edge immediately adjacent thereto, and terminating at said cutting edge, and the curvature thereof being different than the arc of a circle which passes through the cutting edge and has its center in said axial center.

3. In a tool, a stationary head, means to secure said head to a support, adjustable members mounted in said head and projecting therefrom and fixed against endwise movement with respect to said head, and parallel cutting edges on the outer faces of said members, and means mounted for endwise movement with respect to said head and adjustable members to adjust said members into expanded or contracted positions.

4. In a tool, a stationary head, a plurality of parallel adjustable arms mounted in said head and projecting therefrom, one of said

arms having a curved smooth contact surface, and each of the others of said arms having a cutting edge extending lengthwise thereof and parallel to the next adjacent cutting edge.

5. In a tool, a stationary head, a plurality of parallel adjustable arms mounted in said head and projecting therefrom, at least one of said arms having a curved smooth contact surface extending lengthwise thereof.

6. In a tool, a stationary head, and a plurality of adjustable arms mounted in said head, at least one of said arms having a combined cutting portion extending in a straight line and a burnishing portion extending lengthwise thereof.

7. In a tool, a stationary head, and a plurality of adjustable arms mounted in said head for adjustment radially, at least one of said arms having a combined cutting portion extending in a straight line and a burnishing portion extending lengthwise thereof.

8. A tool comprising a head portion, a plurality of cutter arms mounted in said head and projecting therefrom and at least one of which is movable with respect to said head, and actuating means carried by said head and coacting with said movable cutter arm to move said arm with respect to said head and the other of said cutter arms, and resilient means for normally and yieldingly holding said arm against the action of said actuating means.

9. A tool comprising a stationary head portion, a plurality of parallel cutter arms mounted in said head and projecting therefrom and fixed against endwise movement with respect to said head, and having parallel cutting edges lengthwise on said arms, at least one of said arms being movable with respect to said head, and actuating means carried by said head and mounted for endwise movement with respect to said head and cutter arms and coacting with said movable cutter arm to move said arm with respect to said head and the other of said cutter arms.

10. A tool comprising a head portion, a plurality of parallel cutter arms each movably mounted in said head for adjustment radially and projecting therefrom, actuating means carried by said head and coacting with said cutter arms to adjust them radially with respect to each other and said head, and resilient means for normally and yieldingly holding said arms against said actuating means.

11. A tool comprising a head portion, a plurality of parallel cutter arms each movably mounted in said head for adjustment radially and projecting therefrom, an actuating shaft mounted in said head and projecting from said head centrally between said cutter arms and arranged to move said arms radially, and resilient means for normally

- and yieldingly holding said arms against said actuating shaft.
12. A tool comprising a head portion, a plurality of parallel cutter arms each movably mounted in said head for adjustment radially and projecting therefrom, an actuating shaft having a screw threaded engagement with respect to said head and having one end projecting from said head centrally as a tapered portion between said cutter arms and arranged to move said arms radially, the opposite end of said shaft projecting from the opposite side of said head, said head having a rearwardly extending cylindrical portion, and grip means mounted on said opposite end and constituting actuating means for said shaft, and calibrations on said grip means.
13. A tool comprising a head portion, a plurality of parallel cutter arms each movably mounted in said head for adjustment radially and projecting therefrom, an actuating shaft having a screw threaded engagement with respect to said head and having one end projecting from said head centrally as a tapered portion between said cutter arms and arranged to move said arms radially, the opposite end of said shaft projecting from the opposite side of said head, said head having a rearwardly extending cylindrical portion, and grip means mounted on said opposite end and adapted to encircle said cylindrical portion of said head, and calibrations on said grip means.
14. A tool comprising a stationary head portion having a plurality of radially extending slots in one end face thereof, a separate cutter arm movably mounted in each slot and rigidly supported by the walls thereof and extending at right angles from said head and constantly parallel with the next adjacent arm, and actuating means for adjusting said arms radially in said slots.
15. A tool comprising a stationary head portion having a plurality of radially extending slots in one end face thereof, a separate cutter arm movably mounted in each slot and rigidly supported by the walls thereof and extending at right angles from said head and constantly parallel with the next adjacent arm, and actuating means for adjusting said arms comprising a shaft extending through said head and centrally between said arms and having a tapered portion engaging said arms to adjust them radially.
16. A tool comprising a stationary head portion having a plurality of radially extending slots in one end face thereof, a separate cutter arm movably mounted in each slot and rigidly supported by the walls thereof and extending at right angles from said head and constantly parallel with the next adjacent arm, and actuating means for adjusting said arms comprising a shaft ex-
- tending through said head and centrally between said arms and having a tapered portion engaging said arms to adjust them radially, the inner and central portions of said arms being provided with concave tapered surfaces corresponding with the inclination of the tapered portion of said shaft.
17. A tool comprising a head portion having a plurality of radially extending slots, a separate cutter arm adjustably mounted in each slot and projecting from said head, a first set of keyways in the walls of each of said slots, a second set of corresponding keyways in the adjacent faces of each cutter arm within said slots, and a key member fitting in the keyways of said slot wall and said cutter arms, said keys constituting combined keys and guideways for said adjustable cutter arms.
18. A tool comprising a head portion having a plurality of radially extending slots, a separate cutter arm adjustably mounted in each slot and projecting from said head, a first set of keyways in the walls of each of said slots, a second set of corresponding keyways in the adjacent faces of each cutter arm within said slots, said first and said second keyways being substantially semi-circular, and a key member substantially circular in cross section fitting in the said keyways, said keys constituting combined keys and guideways for said adjustable cutter arms.
19. A tool comprising a head portion having a plurality of radially extending slots, a separate cutter arm adjustably mounted in each slot and projecting from said head, a first set of keyways in the walls of each of said slots, a second set of corresponding keyways in the adjacent faces of each cutter arm within said slots, a key member fitting in the keyways of said slot wall and said cutter arms, said keys constituting combined keys and guideways for said adjustable cutter arms, and a plate mounted on said head and bridging the outer ends of said slots and covering the outer ends of said key members.
20. A tool comprising a head portion having a plurality of radially extending slots, a separate cutter arm adjustably mounted in each slot and projecting from said head, a first set of keyways in the walls of each of said slots, a second set of corresponding keyways in the adjacent faces of each cutter arm within said slots, a key member fitting in the keyways of said slot wall and said cutter arms, said keys constituting combined keys and guideways for said adjustable cutter arms, a plate mounted on said head and bridging the outer ends of said slots and covering the outer ends of said key members, and fastening means for securing said plate to said head.

21. A tool comprising a head portion having a plurality of radially extending slots, a separate cutter arm adjustably mounted in each slot and projecting from said head, a first set of keyways in the walls of each of said slots, a second set of corresponding keyways in the adjacent faces of each cutter arm within said slots, a key member fitting in the keyways of said slot wall and said cutter arms, said keys constituting combined keys and guideways for said adjustable cutter arms, a plate mounted on said head and bridging the outer ends of said slots and covering the outer ends of said key members, and a spring between said key members and in engagement with the inner face of each of said plates and the cutter arms and normally yieldingly holding said cutter arms away from said plates.
22. A tool comprising a stationary head portion, expansible cutter arms mounted in said head portion and rigidly supported therefrom and adjustable radially and fixed against endwise movement with respect to said head portion, and an actuating member for adjusting said arms mounted in said head and having one portion thereof screw threaded with respect to said head and another portion cylindrical in shape and slidably mounted in a corresponding bearing portion of said head.
23. A tool comprising a stationary head portion, a plurality of expansible cutter arms mounted in said head portion and rigidly supported therefrom and adjustable radially and fixed against endwise movement with respect to said head portion, said arms being parallel to each other and having parallel cutting portions extending lengthwise thereof, and an actuating shaft for adjusting said arms mounted in said head and movable endwise therein and having a tapered portion in contact with and movable lengthwise of said cutter arms.
24. In a tool, a stationary head, and a plurality of adjustable arms mounted in said head for adjustment radially, each of said arms having a burnishing portion extending in a straight line lengthwise of said arm and at right angles to the path of adjustment of said arms and substantially parallel to the burnishing portion on the next adjacent arm.
25. In a device of the class described, an arm having a guide surface conforming substantially to a segment of a cylinder, and a longitudinally extending cutting edge located at the same radial distance from the axis of the cylinder as said guide surface, but at the opposite side of said axis, and a burnishing surface adjacent said cutting edge, said burnishing surface being curved transversely of the arm and disposed on an arc passing through said cutting edge but lying inside of an arc centered on said axis.
26. In a tool, a head portion and a plurality of parallel cutter arms having a cutting edge extending lengthwise thereof, and having a curved and smooth burnishing surface extending immediately adjacent to and lengthwise of said cutting edge.
27. In a tool, a head portion, and a plurality of parallel cutter arms adjustably mounted in said head portion, at least one of said cutter arms having a cutting edge extending lengthwise of said arm and having a curved and smooth burnishing surface extending immediately adjacent to and lengthwise of said cutting edge and terminating at said cutting edge.
28. In a tool, a head portion, and a plurality of parallel arms extending from said head and grouped about a common center from which the extreme outer portions of said arms are equi-distant, said plurality of arms including a plurality of cutter arms having cutting edges extending lengthwise thereof, a work engaging surface on one of said arms and parallel to said cutting edges, at least one of said cutter arms having also a curved and smooth burnishing surface extending immediately adjacent to the cutting edge and curved from said cutting edge inwardly from the circumference of the circle which would pass through said cutting edges and said work engaging surface.
29. In a tool, a head portion, and a plurality of parallel arms adjustably mounted in said head and extending from said head and grouped about a common center from which the extreme outer portions of said arms are equi-distant, at least one of said arms constituting a cutter arm and having a cutting edge extending lengthwise thereof, a work engaging surface on one of said arms and parallel to said cutting edge, said cutter arm having also a curved and smooth burnishing surface extending immediately adjacent to the cutting edge and curved transversely of the cutter arm and disposed on an arc passing through said cutting edge but lying inside of an arc centered on the common center and passing through the cutting edge and the work engaging surface.
30. A tool comprising a stationary head portion having a plurality of radially extending slots, a separate cutter arm movably mounted in each slot, each cutter arm having one end only in its respective slot and rigidly supported by and from the walls of its slot.
31. A tool comprising a stationary head portion having a plurality of radially extending slots, a separate cutter arm movably mounted in each slot, each cutter arm having one end only in its respective slot and rigidly supported by and from the walls of its slot, the plurality of cutter arms extending from said head in substantially parallel arrangement and with the cutting portions parallel.

32. A tool comprising a combined cutter and polisher of elongated form having a cutting edge extending lengthwise thereof, said edge arranged to cut in one direction only, and said tool having an opposed polishing surface disposed at the other side of the axis thereof from said edge, and that side of the axis carrying the polishing surface being free from cutting edges.

33. A combined reamer and polishing bar having thereon a cutting edge extending lengthwise of said bar, and said bar having an axial work center lengthwise thereof, and a curved and smooth burnishing surface extending lengthwise of said cutting edge and immediately adjacent thereto, the curvature of said burnishing surface being different than the arc of a circle which passes through the cutting edge and has its center in said axial work center.

34. A combined reamer and polishing bar having thereon a cutting edge extending lengthwise of said bar, and said bar having an axial work center lengthwise thereof, and a curved and smooth burnishing surface extending lengthwise of said cutting edge immediately adjacent thereto, and terminating at said cutting edge, the curvature of said burnishing surface being different than the arc of a circle which passes through the cutting edge and has its center in said axial work center.

35. A combined reamer and polishing bar for treating bearings, said bar having a first work engaging portion extending lengthwise of said bar adapted to operate on the metal of a bearing when moved in a given direction, and a second work engaging portion extending lengthwise of and alongside of said first portion and adapted to operate on the metal of a bearing when the relative direction of movement of the tool and bearing are reversed from said given direction, said bar having an axial work center lengthwise thereof, and said second work engaging portion extending beyond the plane of revolution having its center in said axial work center and its circumference passing through and including said first work engaging portion.

36. In a tool, a straight cutter arm having thereon a straight cutting edge extending lengthwise of said arm, and a curved and smooth burnishing surface extending lengthwise of said cutting edge immediately adjacent thereto.

37. In a tool, a straight cutter arm having thereon a straight cutting edge extending lengthwise of said arm, and a curved and smooth burnishing surface extending lengthwise of said cutting edge immediately adjacent thereto, and terminating at said cutting edge.

38. In a tool, a head portion and a plurality of parallel straight cutter arms hav-

ing a straight cutting edge extending lengthwise thereof, and having a curved and smooth burnishing surface extending immediately adjacent thereto and lengthwise of said cutting edge.

39. In a tool, a head portion, and a plurality of parallel straight cutter arms adjustably mounted in said head portion, at least one of said cutter arms having a straight cutting edge extending lengthwise of said arm and having a curved and smooth burnishing surface extending immediately adjacent to and lengthwise of said cutting edge and terminating at said cutting edge.

40. In a tool, a head portion, and a plurality of parallel arms extending from said head and grouped about a common center from which the extreme outer portions of said arms are equi-distant, said plurality of arms including a plurality of cutter arms each having straight cutting edges extending lengthwise thereof, a work engaging surface on one of said arms and parallel to said cutting edges, at least one of said cutter arms having also a curved and smooth burnishing surface extending immediately adjacent to the cutting edge and curved from said cutting edge inwardly from the circumference of the circle which would pass through said cutting edges and said work engaging surface.

41. In a tool, a head portion, and a plurality of parallel arms adjustably mounted in said head and extending from said head and grouped about a common center from which the extreme outer portions of said arms are equi-distant, at least one of said arms constituting a cutter arm and having a straight cutting edge extending lengthwise thereof, a work engaging surface on one of said arms and parallel to said cutting edge, said cutter arm having also a curved and smooth burnishing surface extending immediately adjacent to the cutting edge and curved transversely of the cutter arm and disposed on an arc passing through said cutting edge but lying inside of an arc centered on the common center and passing through the cutting edge and the work engaging surface.

42. A tool comprising a combined cutter and polisher of straight elongated form having a straight cutting edge extending lengthwise thereof, said edge arranged to cut in one direction only, and said tool having an opposed polishing surface disposed at the other side of the axis thereof from said straight cutting edge.

43. A combined reamer and polishing bar of straight elongated form having thereon a straight cutting edge extending lengthwise of said bar, and a curved and smooth burnishing surface extending lengthwise of said cutting edge and immediately adjacent thereto.

44. A combined reamer and polishing bar having thereon a straight cutting edge extending lengthwise of said bar, and a curved and smooth burnishing surface extending lengthwise of said cutting edge immediately adjacent thereto and terminating at said cutting edge.
45. A combined reamer and polishing bar for treating bearings having an axial center extending straight and lengthwise of said bar, said bar having a first work engaging portion extending lengthwise of said bar and the full length of which would lie in a plane passing through it and including

said work center, said first work engaging portion being adapted to operate on the metal of a bearing when moved in a given direction, and a second work engaging portion extending lengthwise of and alongside of said first portion and adapted to operate on the metal of a bearing when the relative direction of movement of the tool and bearing are reversed from said given direction.

In testimony whereof we affix our signatures.

FRANK O. EWELL.

WILLIAM MEADE SHUEY.
